UNITED STATES PATENT OFFICE.

AUSTIN F. JACKSON, OF TAUNTON, MASSACHUSETTS, ASSIGNOR TO THE REED & BARTON CORPORATION, OF SAME PLACE.

DESIGN FOR A HANDLE FOR SPOONS.

SPECIFICATION forming part of Design No. 22,105, dated January 10, 1893.

Application filed October 14, 1892. Serial No. 448,907. Term of patent 14 years.

To all whom it may concern:

Be it known that I, AUSTIN F. JACKSON, of Taunton, in the county of Bristol and State of Massachusetts, have invented and produced a certain new and useful Design for Handles of Spoons and other Similar Articles, of which the following is a specification, reference being had to the accompanying drawings, in which—

10 Figure 1 represents the front or obverse side of a spoon showing my design applied to its handle. Fig. 2 shows the back or reverse side of the same.

15 The leading feature of my design is a volute spiral scroll A whose marked characteristic is that of a closely coiled feather which starts at one side of the handle near the end, passes around the margin of the end of the handle and then, turning in, is curled with a 20 diminishing radius toward the center. Just below it is a smooth panel B having upon

each side a scrolled border b whose ends turn inwardly and are scrolled. Shoots and curled stems a are also formed upon the shank of the handle and extend along the margin up to the border of the plain panel B where they terminate with an outward roll.

25 The reverse side of the spoon handle corresponds in outline to the obverse and has a series of short marginal ribs curving inwardly at their ends which give contour to the handle, and terminate at their ends in scrolled bulbs, or inturned rolls.

Having thus described my invention, what I claim is, 30 The design for the handles of spoons and other similar articles as herein shown and described.

AUSTIN F. JACKSON.
